UNITED STATES PATENT OFFICE.

ABRAHAM L. A. HIMMELWRIGHT, OF NEW YORK, N. Y., ASSIGNOR TO THE NEW JERSEY WIRE CLOTH COMPANY, OF TRENTON, NEW JERSEY, A CORPORATION OF NEW JERSEY.

CONCRETE BEAM PROTECTION.

SPECIFICATION forming part of Letters Patent No. 786,289, dated April 4, 1905.

Application filed July 16, 1903. Serial No. 165,787.

To all whom it may concern:

Be it known that I, ABRAHAM L. A. HIMMELWRIGHT, a citizen of the United States, residing at New York, county of New York, and State 5 of New York, have invented certain new and useful Improvements in Concrete Beam Protection, fully described and represented in the following specification and the accompanying drawings, forming a part of the same.

- 10 The object of the present invention is to provide an improved fireproof protection for the under side of beams in concrete floor constructions. It is now common in fireproof buildings to employ a layer of concrete on the under side of the iron beams, which is filled in with and forms a part of the floor concrete. It has been found necessary in practice to provide some means for supporting this layer of concrete, and it has proven difficult to provide 15 such means which will efficiently support the concrete and at the same time permit the concrete to be filled in below the beams to the centering in such a manner as to form a solid integral layer of concrete. I have found that 20 the desired result can be secured by the use of clips on the flanges of the beams provided with portions projecting downward into the layer of concrete and preferably hooked to give a greater support for the concrete. I 25 have found that these clips may be placed at a considerable distance apart, so that the concrete can readily be worked down under the beam between and around the clips and as there is no metal construction below the beams 30 except these separated clips a solid continuous body of concrete thoroughly molded together may readily be formed, so that with such solid integral body of concrete the separated clips furnish sufficient support.
- 35 The invention will now be described in connection with the accompanying drawings, forming a part of this specification, in which a construction embodying the invention in the preferred form is illustrated, and the features 40 forming the invention will then be specifically pointed out in the claims.
- 45 In the drawings, Figure 1 is a section of a concrete floor transversely to the beams and

showing the structure complete before removal of the centering. Fig. 2 is a cross-section of the structure shown in Fig. 1 with the centering removed. Fig. 3 is a detail section of the beam protection and a portion of the floor, showing also the plaster finish. Fig. 4 is a detail view of the form of clip shown in 50 Figs. 1 to 3.

The beams A are the common flanged beams and the floor is shown as consisting of the ordinary web of concrete B, with bodies of concrete C extending downward along the webs 55 of the beams and the beam protection of concrete D extending around and under the bottom flanges of the beams. The wooden centering E (shown in Fig. 1) is the temporary wooden centering used to support the concrete 60 while it is filled in and during setting and may be of any suitable construction. The concrete protection D for the lower flanges and bottom of the beams is supported by the clips F, placed on the beam-flanges at suitable 65 distances, such as to permit the concrete to be worked under the beam and around the clips in filling in. These clips F may be of other forms than that shown, but in order to support the concrete must be provided with arms 70 projecting into the concrete, and these arms are preferably inclined outward or inward and may be hooked, so as to provide a better support for the concrete. The form of clip shown will be found very efficient and may 75 be made cheaply from waste bits of metal. These clips consist of narrow metal plates, slit at their opposite ends, so as to provide a pair of arms 1, which are bent upward over the flange of the beams to hold the clip in 80 place, a pair of outwardly-inclined and hooked arms 2 and a pair of inwardly-inclined and hooked arms 3, which arms 2 3 are embedded in the concrete and strongly support the latter.

In building the construction shown the 85 temporary centering E is first put in place, and the concrete protection for the lower flanges and bottom of the beams is first filled in, being worked by any suitable tool down into the space below the beam and around and 90 between the clips F, so as to form a solid in-

95

tegral body of concrete. A solid body of concrete surrounding and extending about the bottom flanges of the beams having thus been formed, the upper part C of the concrete 5 about the beams is filled in and the rest of the structure completed as usual in such constructions. After the concrete is set the temporary centering E is removed, and the concrete may then be covered by a plaster finish 10 G, as shown in Fig. 3, or the concrete may be left exposed, or a ceiling may be suspended below the beams, according to the character of the structure desired.

What I claim is—

15 1. In a concrete floor or similar structure, a beam protection consisting of a body of concrete extending around and below the bottom flanges of the beams and supported solely by the beams and clips arranged at intervals on 20 the flanges and provided with arms extending below the beams and embedded in the concrete, substantially as described.

25 2. In a concrete floor or similar structure, a beam protection consisting of a body of concrete extending around and below the bottom flanges of the beams and supported solely by the beams and clips arranged at intervals on the flanges and provided with inclined arms 30 extending below the beams and embedded in the concrete, substantially as described.

35 3. In a concrete floor or similar structure, a beam protection consisting of a body of concrete extending around and below the bottom flanges of the beams and supported solely by the beams and clips arranged at intervals on the flanges and provided with inclined hooked

arms extending below the beams and embedded in the concrete, substantially as described.

4. In a concrete floor or similar structure, a beam protection consisting of a body of concrete 40 extending around and below the bottom flanges of the beams and supported solely by the beams and clips arranged at intervals on the flanges and provided with arms some of which are inclined downward and outward and others downward and inward from the beam flange and embedded in the concrete, substantially as described.

5. Beam-protection supporting-clip F provided with arms 1 for engaging the flange of 50 the beam to hold the clip in place, and inclined arms 2, 3 on the opposite side of the clip from the arms 1, some of which inclined arms extend downward and outward and others downward and inward, substantially as 55 described.

6. Beam-protection supporting-clip F provided with arms 1 for engaging the flange of the beam to hold the clip in place, and inclined arms 2, 3 on the opposite side of the clip from 60 the arms 1, said arms 2, 3 being hooked at their ends, and some of said arms extending downward and outward and some downward and inward, substantially as described.

In testimony whereof I have hereunto set 65 my hand in the presence of two subscribing witnesses.

ABRAHAM L. A. HIMMELWRIGHT.
